UNITED STATES PATENT OFFICE.

ABBOT AUGUSTUS LOW, OF HORSESHOE, NEW YORK.

HYDROCARBON-MOTOR.

SPECIFICATION forming part of Letters Patent No. 793,886, dated July 4, 1905.

Application filed December 3, 1903. Serial No. 183,570.

To all whom it may concern:

Be it known that I, ABBOT AUGUSTUS Low, a citizen of the United States, residing at Horseshoe, St. Lawrence county, and State 5 of New York, have invented certain new and useful Improvements in Hydrocarbon-Motors, of which the following is a specification, sufficient to enable others skilled in the art to which the invention appertains to make and 10 use the same.

This invention relates to marine motors which are actuated by the explosion of vaporized hydrocarbon and is designed to effect the practically-noiseless discharge of the re- 15 sultant gases and other products of combustion.

The invention consists in the novel construction, combination, and arrangement of parts, all as more fully hereinafter described, 20 shown in the drawing, and then particularly pointed out in the appended claims.

The accompanying drawing illustrates the construction embodying the invention and, with the characters of reference thereon, 25 forms a part of this specification.

B represents the hull of a boat or marine vessel of any kind submerged below the water-line *w w*.

E is a gas, kerosene, or other hydrocarbon 30 engine of any description, the operative parts and connections being omitted in the drawing, with the exception of the power-shaft *a* and the discharge-conduit D. The discharge-conduit D is provided with a relief-valve or 35 damper *d*, which may be opened in whole or in part while the engine is started or to regulate or modify the tension within the said discharge-conduit, if desired. The lower portion *d'* of the discharge-conduit D is situated

40 in the conical water-channel C, extending across the hull of the vessel and opening under the water-line on both sides thereof so as to provide for a free current of water through said conical channel C, and this current is 45 augmented and insured by the discharge of the products of combustion from the end of the pipe *d'*, which latter is provided with a check-valve *d²* to prevent back pressure and to exclude the water from the discharge-con-

duit. By this means a continuous supply 50 of fresh cold water is brought into contact with the discharge-pipe *d'*.

The suction created in the discharge-conduit is augmented by the condensation of the products of combustion by the fresh cold wa- 55 ter in the jacket C, the partial vacuum thus created reducing the resistance to the minimum and adding to the effective power of the motor. This decrease in resistance is such that the diameter of the discharge-pipe 60 D may be materially reduced, as indicated in the drawing, with beneficial results.

The water-channel C is inclined slightly with relation thereto, as shown in the drawing, so that the discharge-port *c* is lower than 65 the upper portion of the top of the inlet *c'*, the discharge-pipe of course being arranged to eject the products of combustion toward said discharge-port *c*. I also provide the wider end *c'* of the channel, which con- 70 stitutes the mouth or inlet-port thereof, with a screen *s* for the purpose of excluding solid matter. The water-channel C is made in the form of a truncated cone, the longitudinal axis of which is inclined downwardly from 75 the horizontal, so that the smaller or truncated discharge end of the said conical water-channel is farther below the water-line than the top of the inlet. By this means the convergent walls of the said channel not only 80 guide and concentrate the flow of fresh cold water around the discharge end of the channel or conduit, but by having the discharge-conduit located in said channel and discharging at the smaller end of the same near its 85 discharge into the surrounding water all tendency or liability of backflow within the said conical water-channel is counteracted.

What I claim as my invention, and desire to secure by Letters Patent, is— 90

1. In a motor-driven vessel, the combination with an internal-combustion motor for driving the same, of a water-channel in the shape of a truncated cone extending across the hull of the vessel below the water-line, 95 and an exhaust-pipe from the motor located in said channel and discharging at the smaller end of the same near its delivery into the

surrounding water for the purpose of counter-acting backflow within said conical water-channel.

2. In a motor-driven vessel, the combination with an internal-combustion engine for driving the same, of a water-channel in the shape of a truncated cone extending across the hull of the vessel below the water-line, and an exhaust-conduit for the products of combustion, a relief-valve in said conduit outside the said channel, and a check-valve in said

conduit within said channel, said exhaust-conduit extending within the water-channel axially thereof and terminating within the same in proximity to the delivery end of said channel into the surrounding water for the purpose of counteracting backflow within said conical water-channel. 15
